US00D614187S

(12) **United States Design Patent**
Blanchard

(10) **Patent No.:** **US D614,187 S**
(45) **Date of Patent:** **** Apr. 20, 2010**

(54) **INPUT DEVICE**

(75) Inventor: **Stéphane Jacques Blanchard,**
Singapore (SG)

(73) Assignee: **Razer (Asia-Pacific) Pte Ltd**, Singapore
(SG)

(**) Term: **14 Years**

(21) Appl. No.: **29/304,080**

(22) Filed: **Feb. 25, 2008**

(51) LOC (9) Cl. **14-02**

(52) U.S. Cl. **D14/402**

(58) **Field of Classification Search** D14/402–410,
D14/356, 388, 389, 383–385, 417, 426; 345/156–167;
463/36–38; 358/471, 473

Assistant Examiner—Deanna Fluegeman

(74) *Attorney, Agent, or Firm*—Conley Rose, P.C.

(57) **CLAIM**

The ornamental design for an input device, as shown and described.

DESCRIPTION

FIG. 1 is the perspective view of an input device;

FIG. 2 is a front elevational view of the input device of FIG. 1;

FIG. 3 is a rear elevational view of the input device of FIG. 1;

FIG. 4 is a top plan view of the input device of FIG. 1;

FIG. 5 is a bottom plan view of the input device of FIG. 1;

FIG. 6 is a side elevational view of the input device of FIG. 1; and,

FIG. 7 is another side elevation view of the input device of FIG. 1, the opposite side of the side elevational view as shown in FIG. 6.

The broken lines in the figures depict portions of the input device that form no part of the claimed design.
